DENTAL CABINET

Application filed October 31, 1929. Serial No. 403,829.

This invention relates to improvements in containing receptacles or cabinets adapted to receive dental devices and materials, and more particularly suited for household or domestic use.

Its objects are to provide a holder or container of dental brushes, tooth-cleansing substances, tooth-picks, dental floss and similar devices and materials for cleansing and preserving the teeth, which will be low-cost and easily available for the usual family; adapted to maintain all of the brushes and other contents in a protected, sanitary and convenient aggroupment; which will, by its characteristics, induce cleanly dental habits; which will, by the position of its brush-holding means, prevent wear and cutting of the lowermost line of bristles; which will maintain the bristles free from external contacts; which will be economical of space and easily attached to a wall or placed on any article of furniture or packed for travel; so organized as to maintain definite separation of the individual brushes, and prevent contact between them and which will permit free ventilation of the container. Other objects will appear as this description proceeds.

In general, the container, or cabinet, is designed to fulfill a definite need which has gradually come with the general advance in civilization and knowledge of hygiene, together with the better understanding of the needs of caring for the teeth; for their own preservation and for promoting and maintaining general health.

As before recited, this invention includes the arrangement, whereby the aggroupment of all of the devices and materials in a compact, convenient and accessible package, and the consequent ease of performing not only the usual cleansing of teeth by brushing but more thorough attention by means of floss and picks, combined with some attractiveness of the cabinet itself, will induce the use of the facilities thus furnished.

In general, this invention comprises a small cabinet, preferably of thin metal and preferably given an external ornamental finish. The container has a door which closes the interior and the therein contained mate-

rial or substances. Inside the container is a vertical, curved wall, or partition which forms a resting place for a dentifrice container or a plurality thereof. The bottom of the compartment is inclined so that any long object, such as a cylindrical tube, similar to ordinary tooth-paste containers, resting on the said inclined bottom, will be automatically caused to tilt, so that its upper end will rest against the said wall, or partition, preventing any tendency to fall outward. The individual containers for the several tooth-brushes are so fashioned and located that each brush is definitely separated from all of the others; each brush is set in a vertical position so that it will drain and dry most effectively, and the brushes are each supported by their downmost ends by a V-shaped trough-like support in which the lower ends of the brush handles rest and which constitutes the sole vertical support of the brushes, the bristles being all held well above every part of the compartment surrounding the brush, so that the weight of the brush is not carried by the bristles, but only by the lower end of the brush-handle. Preferably, some individual identification is placed on each of the brush holders, such as a number, letter, or any desired marking, by stamping or coloring.

With the above and other objects in view, this invention consists in the new and useful provision, formation, construction, combination and interrelation of parts, members and features, all as hereinafter disclosed, shown in the drawings and finally pointed out in the claim.

This invention is part of the disclosure of patent application, Serial No. 364,614, filed by us May 20, 1929.

In the drawing:

Fig. 1 is a front elevation of one form of the invention;

Fig. 2 is a plan thereof, showing the door open;

Fig. 3 is a vertical section of same on line 3—3 of Fig. 2.

As shown in the figures, there is a container or cabinet of which A is a lower apron, B is a door adapted to swing about a transverse

pinhole 19, across the cabinet just at the upper edge of the apron A. Hence, the door B is hinged to swing downwards to open. A single wide knuckle, 29, is formed by bending the bottom end of the door into a tube which surrounds the pinhole. On the inner surface of the sheet metal door B are formed two compartments, 23 and 26, to hold a tube of dental floss and tooth-picks, respectively, as shown. These compartments are formed by bending a piece of thin sheet metal H in the shape desired and fastening it to the inner surface of the door at points of contact, 11. The intermediate partition, or wall, against which the tubes of dentifrice lean, is provided with two substantially vertical, concave depressions for the reception of two tubes, as shown, so that the entire space transversely across the cabinet is occupied by these receptacles.

Intermediate the rearmost wall G of the cabinet and the pair of tube-holding concave compartments, is positioned the plurality of handle-surrounding containers for the tooth-brushes, made by bending a sheet of thin metal J into the desired form and fastening the bent plate to contact with the intermediate vertical sheet N, at contact points, 12, thereby forming the individual handle compartments as shown. A handle-supporting, V-shaped trough, formed by fastening a narrow strip L, diagonally onto the inner surface of the intermediate plate N, forming a bottom rest for the brush handles which fixes the height of the brushes.

It is to be observed that in this construction, the uppermost edge of the compartment channels is positioned at an ample distance below the bristle heads of the brushes so that the lowermost row of bristles can never contact with the uppermost edge of the handle surrounding compartments.

While numerous variants of this invention are possible, it is to be observed that any complete form will have the following characteristics:

- (1) Each tooth-brush is separated from its neighbor on either side by a definite wall.
- (2) All brushes are held in an upright position.
- (3) All brushes are supported on their bottom ends; not on the bristles.
- (4) Tooth-paste or dentifrice tubes automatically lean towards the receptacle of the cabinet provided for them and have no tendency to fall out of the container.
- (5) No matter how placed, packed or hung, the bristles of the tooth-brushes always clear the wall and make no contact with any surface against which the cabinet may rest.
- (6) A single door gives access to all of the interior of the cabinet and to all of the devices and material therein contained.
- (7) The arrangement of individual compartments is such that all space is used or

useful, so that the cabinet is essentially compact, and small for the volume of the devices and materials which it is arranged to contain.

(8) Every form is cheaply produced as indicated in the several designs and accompanying descriptions here used to illustrate the general form of the device.

(9) Every design provides for containing all of the several kinds of devices and materials needed for complete tooth cleaning such as is done in the household.

Having described our invention in connection with illustrative embodiments, forms, proportions and arrangement of parts, it will be understood that many variants thereof are possible to those skilled in the art, and our invention, in its broader aspects, is not limited to the specific construction herein described and shown, as changes in the sizes, proportions, configurations, arrangements, assemblage, materials, juxtaposition and mechanical relations, as well as additions, omissions, substitutions, combinations and alterations of forms, parts, members and features, may be made without departing from the broad spirit of this invention.

Having thus described our invention, we claim and desire to secure by Letters Patent:

A device of the character disclosed, including a casing having a plurality of brush holders formed and arranged for maintaining the brushes in upright position with the bristle heads above said holders; said casing having a compartment for a dentifrice holder and the like; said casing having an inclined bottom portion normally disposing such dentifrice in inclined position in the casing, and a closure for said opening provided with means for mounting thereon other dental requisites.

In testimony whereof, we have signed our names to this specification at Los Angeles, Calif., this 24th day of October, 1929.
